[57] CLAIM

The ornamental design for a set of chess pieces, as shown and described.

DESCRIPTION

FIGS. 1-6 are top plan views of chess pieces representing a king, knight, queen, rook, pawn and bishop, respectively, and constituting a first embodiment of my new design;

FIGS. 7-12 are top plan views of chess pieces constituting a second embodiment of my new design;
The chess pieces are of no appreciable thickness.
